FILM STRIP CARTRIDGE

Gerald T. Thompson, 10533 Arrington Ave., Downey, Calif., and Richard P. Fuller, North Hollywood, Calif.; said Fuller assignor to said Thompson

Filed Aug. 29, 1960, Ser. No. 62,009

Term of patent 14 years

(Cl. D61—1)

Figure 3 is a side elevation of the cartridge of Figures 1 and 2 showing it inserted within a portable film viewer which is shown in phantom for illustrative purpose only;

We claim:

The ornamental design for a film strip cartridge, as shown and described.
